UNITED STATES PATENT OFFICE.

CHARLES A. S. LOCKWOOD, OF HAVERSTRAW, NEW YORK, ASSIGNOR TO HIMSELF AND WILLIAM H. KNAPP, OF RED BANK, NEW JERSEY.

PAPER BAG.

SPECIFICATION forming part of Letters Patent No. 242,664, dated June 7, 1881.

Application filed March 18, 1881. (Model.)

To all whom it may concern:

Be it known that I, CHARLES A. S. LOCKWOOD, of Haverstraw, Rockland county, New York, have invented a new and useful Improvement in Paper Bags, of which the following is a specification.

Figure 1 is a plan view of a blank for one of my improved bags ready for folding. Fig. 2 represents the bag with the bottom nearly 10 formed, and Fig. 3 represents the bag with the bottom fully formed.

Similar letters of reference indicate corresponding parts.

The object of this invention is to facilitate 15 the manufacture of paper bags and economize the use of stock in their construction.

In making my improved bags the paper is cut into rectangular shape and of such dimensions as will form bags of the required size. 20 To the lower edge of the blank A is pasted or upon it is formed a rectangular piece, B, to form the bottom of the bag. The blank A is then folded so that the side edges will overlap, and the said overlapped edges are pasted 25 together. The part C of the lower edge to which the flap B is attached and the part D, opposite the said flap, are folded down toward each other in triangular form, bringing the flap B beneath the edges of the said parts C 30 D, leaving a space between their edges. The end parts, E F, of the flaps formed by making

the folds C D are then folded down, so that their edges will overlap the bottom B, leaving a space between their edges, as shown in Figs. 2 and 3.

In making the bags each fold is pasted down so as to form a close bottom, with no open seams or pockets for the substance put in the bag to get into. In the case of large bags a second piece or flap, B, can be attached to the lower 40 edge of the blank A in such a position as to be directly opposite the flap B when the side edges of the said blank are folded together, so that when the formation of the bag-bottom is completed one of the flaps B will be upon 45 the inner side of the bag-bottom, and the other upon the outer side of the said bottom.

By this construction strong and reliable bags are produced, and a saving of fully one-tenth of the stock is effected over the ordinary construction..

Having thus described my invention, I claim as new and desire to secure by Letters Patent

A paper bag having a central flap, B, with 55 the folds C D E F arranged thereupon, as shown and described.

CHAS. A. S. LOCKWOOD.
